UNITED STATES PATENT OFFICE

ALEXANDER BOYNTON, OF SAN ANTONIO, TEXAS

AUTOMATIC WELL-FLOWING DEVICE

Application filed December 1, 1927. Serial No. 237,051.

This invention relates to improvements in automatic well flowing devices, relating more particularly to an improvement in the structure of certain applications presently identified.

An object of the invention is to provide a combination differential or a pressure fluid and liquid velocity control device which embodies a flap which is movable towards a position at one side of the path of movement of a liquid stream or column by the velocity of such stream thereby permitting the various positioning of the pressure fluid control valve as fully developed below.

Other objects and advantages appear in the following specification reference being had to the accompanying drawing in which,

Figure 1 is a longitudinal section of the improved control device, portions of the associated well tubing and casing being shown,

Figure 2 is a cross section on the line 2—2 of Figure 1,

Figure 3 is a detail perspective view of the foregoing flap or valve depressor.

The subject matter herein disclosed is associated with the subject matter of other inventions of the same series, particularly in Case #15, filed Nov. 21, 1927, Serial #234,775 and Case #17 filed Dec. 10, 1927, Serial #239,137 from each of which it differs by a curved flap valve, hinged off from the center of gravity and provided with a heel to depress a certain plunger or valve element. It is deemed unnecessary to expound the mode of use and theory of the device down to the minutest details because that has been adequately done in prior disclosures. A brief introduction will be satisfied by the statement that both the pressure of the lifting fluid and the liquid column lifted by said fluid mutually contribute to the control of the pressure fluid.

Reference is made to the drawing. The well casing 1 and adjoining sections 2 and 3 of the well tubing are to be recognized at once.

The tubing section 2 is screwed into one end of a portion 4 constituting one part of a valved body. This portion is screwed or otherwise fixed at 5 to a second portion 6 of the valve body.

A valve element or plunger 7 is situated

and vertically movable in a bore or passageway 9 formed in a lateral enlargement 8 of the lower body portion 6. The formation of the passageway includes a valve seat 10 with which a bevelled end of the valve element is engageable when the valve element is subjected to a predetermined differential pressure.

Bores 11 and 12 in the portions 4 and 6 constitute a liquid chamber in the valve body. A slight curvature of the bore 12 affords an accommodation for the plunger 7 and the passageway 9 thereof without making the lateral enlargement 8 of undue size and without unduly enlarging the diameter of the assembly. A flap valve 13 occupies the bore 11 whence it is movable into a lateral pocket 17 by the combined efforts of an upward thrust imposed upon the valve element 7 by the pressure fluid as well as the velocity of the liquid in the adjacent chamber. An extension 16 of the pocket 17 provides for hinging the flap 13 off center.

A heel 15, included in the construction of the flap reaches into the extension 16 where it receives the pivot pin 18. The heel is capable of resting upon a shoulder 19 afforded by the exposed upper surface of the valve body portion 6. The free end of the flap rests against the far side of the bore 11 at the same time. The flap is made concave at 14 thereby to more nearly harmonize with the bore 11 especially when the flap is retired within the pocket 17 as indicated by the dotted lines. It is to be observed that the flap becomes larger toward the base or heel at which point the cross sectional aspect discloses the concavity 14 to be semi-circular (see Figure 2).

A recess 20 is intended to receive the adjacent plunger end 21. The latter is slightly spaced from the recess when the plunger or valve element is in resting position upon the edge of the inlet bore 22 in the bushing 23. The unimpeded movement thus afforded the valve element provides for an initial influx of the pressure fluid as fully developed in kindred embodiments of the invention. The peculiar shape of the flap 14 obviates the need of a spring to return the flap into posi-

tion in the adjacent bore 11 of the liquid chamber.

The operation is readily understood. It is assumed that the well casing 1 contains a fluid (gas or air) under pressure. It is desired to utilize the pressure fluid for the lifting of a column of liquid (oil for example) in the well tubing 2, 3. Certain relative conditions of the liquid column introduce what is consistently identified in associated patent applications, for example, Case #1, filed April 5, 1927, Serial #188,144, as differential pressures.

As the pressure differential increases, the thrust thereof upon the valve element 7 causes the latter to rise in the passageway 9 so that the end 21 lifts the curved flap 13 with the heel 15 of which the plunger end has by now come into engagement. The introduction of pressure fluid into the liquid of the adjacent chamber in the valve body revives the movement of the liquid column, the upward movement or velocity of which tends also to lift the curved flap 13 and retire it in the pocket 17 from the path of the liquid in the chamber.

When the velocity of the liquid column diminishes the flap or depressor 13 tends by force of gravity, to resume the original diagonal position across the bore 11. In following this tendency the heel 15 of the flap depresses the end 21 and valve element 7 so that the latter disengages the upper seat 10, with which it may be assumed that engagement has been made, permitting external pressure fluid to again flow into the valve body and well tubing to accelerate the upward movement of the liquid column. A recurrence of these acts obtains whenever, and as often as, the differential pressure and liquid velocity diminish to a predetermined degree.

I claim:

1. Apparatus of the character described comprising a body having a conduit for the passage of liquid and a communicating passageway for the introduction of lifting pressure fluid, and means respectively situated in the chamber and in the passageway each being independently and solely movable by the opposing effects of gravity and of liquid and pressure fluid impacts but mutually co-active for the control of the pressure fluid flow through said passageway.

2. Apparatus of the character described comprising a body having a conduit for the passage of a liquid column and a communicating passageway for the introduction of lifting pressure fluid, a flap hinged in the chamber being movable to various positions by variations in the velocity of the liquid column and by resulting variations in the effect of gravity thereupon, and a valve element unrestrictedly operable in the passageway by the thrust thereupon of pressure fluid flowing through the passageway, the various

respective positions of the valve element being determined by said foregoing means.

3. Apparatus of the character described comprising a body having a chamber and a passageway affording communication between the chamber and the exterior, a valve element movable toward a closing position in said passageway by the thrust of pressure fluid imposed thereupon, and a pivoted flap disposed in the chamber assuming various positions by virtue of the counteraction of a fluid column moving in one direction and gravitation in the opposite direction, said flap having a heel to regulate the position of said valve element.

4. Apparatus of the character described comprising a body having a chamber and a passageway affording communication between the chamber and the exterior, a valve element movable toward a closing position in said passageway by the thrust of the pressure fluid thereagainst, and a flap pivoted off center in the chamber including a heel superimposed upon a portion of the valve element for the purpose described.

5. Apparatus of the character described comprising a body with a chamber and a passageway affording communication between the chamber and the exterior, a lateral pocket formed upon the body and communicating with the chamber, a valve element movable in the passageway and having an end extending toward said pocket, a flap occupying the chamber and being capable of retirement into said pocket, said flap including a heel superimposed upon said end, and means by which the heel is pivotally mounted in said pocket in off center relationship to the chamber.

6. Apparatus of the character described comprising a body having a chamber with a passageway affording communication between the chamber and the exterior, a lateral pocket formed in the body including an extension both communicating with the chamber, a valve element in the passageway having an end directed toward said pocket, a flap occupying the chamber but being movable into retirement in said pocket thus leaving the chamber clear, said flap having a heel superimposed upon said end and occupying the extension, and means by which the flap is pivotally mounted upon said heel in said extension.

7. Apparatus of the character described comprising a body composed of two portions each having bores which communicate to form a chamber, a lateral pocket formed in one of the portions leaving an exposed resting surface upon the other portion, said other portion having a passageway terminating at the resting surface and affording communication of the chamber with the exterior, a valve element situated in the chamber having an end extending toward said resting

surface, and a flap pivoted in said lateral pocket including a heel resting upon said surface in superimposed relationship to said end and extending across the chamber into 5 resting position upon a wall of the bore.

8. Well flowing apparatus comprising a casing and tubing for the occupancy of liquid to be lifted, and a lifting device incorporated in the well tubing including one member 10 having a heel, which member is oppositely movable by the velocity of a liquid column and by the effects of gravity whereby said member assumes varying positions, and a second member which is movable in one direction by the effects of gravity and by the 15 action of said heel, and in the opposite direction by the thrust of entering pressure fluid the various positions last assumed by the second member being controlled by said heel 20 during the various positions of said first member.

9. A valve comprising a body having a conduit and a passageway connecting the conduit with the outside of the body, a valve 25 element operable in the passageway, and a flap operable in the conduit, having a heel pivoted close to the valve element so that the heel may bear upon a portion of the valve element.

30 10. A valve comprising a body having a conduit and a passageway connecting the conduit with the outside of the body, a valve element operable in the passageway, a flap operable in the conduit, and a heel on the 35 flap adjoining an end of the valve element, being pivoted upon the valve body and having a recess to receive the end of the valve element and affording a slight space between said end and the heel when the valve element 40 is in a rested position, permitting an unimpeded preliminary movement of the valve element.

11. A valve comprising a body having a bore with a communicating lateral pocket, 45 and a passageway connecting the outside of the body with the bore at said pocket, the body having a bore adjacent to the passageway communicating with the first bore but having a slight curvature to afford an accommodation for the passageway and an avoidance of an unduly large size of the valve body, a valve element operable in the passageway having an end extensible into the pocket, and a flap pivoted upon the body at 50 one side of the pocket, having a heel co-acting with said end.

Signed at San Antonio in the county of Bexar and State of Texas this 9th day of November, A. D. 1927.

60 ALEXANDER BOYNTON.
